(57) **CLAIM**

The ornamental design for a three tier planter, as shown and described.

DESCRIPTION

FIG. 1 is a front view of a three tier planter showing our new design, back, left side, and right side views each being identical;

FIG. 2 is a top view of the three tier planter;

FIG. 3 is a bottom view of the three tier planter;

FIG. 4 is a top front side perspective view of the three tier planter; and,

FIG. 5 is a cross-sectional view of the three tier planter taken along line 5-5 of FIG. 2.
